UNITED STATES PATENT OFFICE.

ALEXANDER G. GORDON, OF WINSTON-SALEM, NORTH CAROLINA.

MACHINE FOR CUTTING, CREEASING, AND FOLDING.

Application filed June 21, 1920. Serial No. 390,541.

To all whom it may concern:

Be it known that I, ALEXANDER G. GORDON, a citizen of the United States, residing at Winston-Salem, in the county of Forsyth 5 and State of North Carolina, have invented certain new and useful Improvements in Machines for Cutting, Creasing, and Folding, of which the following is a specification.

My invention relates to a machine for cutting, creasing and folding paper wrappers for cigarette papers or similar articles, and the object of my invention is to provide a machine that will perform the operations of cutting, creasing and folding wrappers in sequence.

I attain these objects by the mechanism illustrated in the accompanying drawings, in which—

Fig. 1 is a front elevation of the entire machine showing the motor and belt drive;

Fig. 2, an end elevation showing gearing, feed table and tray for receiving wrappers after passing through the machine;

Figs. 3 and 4 are enlarged views of gearing, showing relative positions of cutters, creasers and folding rollers;

Fig. 5 is a vertical section on line A—A, of Fig. 3;

Fig. 6 is a vertical section on line B—B, Fig. 3;

Fig. 7 is a vertical section on line C—C, Fig. 3;

Fig. 8 is a detail view of cutters;

Fig. 9 is a detail view of the creasers; and

Fig. 10 is a diagrammatic plan view of the back of a printed sheet.

Similar numerals refer to similar parts throughout the nine views. The body 1, legs 2—2, and braces 3—3 constitute the frame 40 work of the machine. The motor 4, mounted on plate 5 which is secured to braces 3—3, through shaft 6 drives pulley 7, which in turn drives pulley 8 by the belt; pulley 8 is mounted on shaft 9 which in turn drives 45 pulley 10. The loose and tight pulleys 11 and 12 are driven by pulley 10 through belt drive, and tight pulley 12 drives shaft 13, which in turn drives gear 14. Gear 14 is one of a train of nine gears on end of machine 50 and drives crimper shafts 15 and 16 through gears 17, 18 and 19, and cutter shafts 20 and 21, and feed roller shaft 62 through gears 17, 18, 22, 23, 25 and 26.

The lower members of the feeding, cutting, 55 creasing, and folding mechanisms are mount-

ed respectively on the shafts 62, 20, 15 and 13, these shafts being mounted on the frame of the machine.

The upper members of these mechanisms are mounted on shafts 31, 21, 16 and 57 60 which are in turn carried by a series of pivoted arms 32, 27 and 50, so that they can all be raised, whenever necessary, upwardly from the bed portion of the machine.

The feeding mechanism comprises a driven feed roller 29 keyed to the shaft 62 and a loose feed roller 30 secured to the shaft 31 which in turn is carried on arms or brackets 32, having adjusting screws 70, the brackets being pivoted on a fixed shaft 28 mounted 70 on the frame of the machine.

The cutting mechanism comprises upper and lower cutters 33, which as shown in Fig. 5 are held in place by washers 34 and 35, the washers 34 being keyed to the shafts 20 and 21. The cutting disks 33 which may be of any suitable shape are held in spaced position by sleeves 36, 37, 38, 39 and 40. The creasing mechanism comprises upper and lower rotatable members 41 and 44 as 80 shown in Fig. 6. These members are keyed respectively to shafts 15 and 16 and are secured thereto by set screws 46, 43. The upper or male creasing member 41 is provided with a shoulder or shoulders cooperat- 85 ing with a corresponding groove or grooves in the lower or female creasing member 44. The upper members of both the cutting and creasing mechanism are carried on arms 27 pivoted on the shaft 28, the arms being pro- 90 vided with adjusting screws 56, and being secured to the shaft 28 by set screws 55.

The folding mechanism comprises a lower member consisting of a roller 47 keyed on the shaft 13 and having preferably the shape 95 shown in Fig. 7. The loose folding rollers 49 are mounted on shafts 57 passing through the forward ends of bell crank levers 50 which are pivoted on pins 52 carried in turn by a yoke piece 51 which is clamped on the 100 shaft 28 by a bolt 61. Springs 53 mounted on the screws 54 keep the rollers 49 pressed against the driven roller 47.

The lower rotating members of each of these cooperating devices are positively 105 driven by the gear train shown in Figs. 2 and 3.

The feed table 58 is secured to the frame of the machine by brackets 59. The receiving trays 60 are made of thin sheet metal and 110

are mounted on the board 61 which is secured to the frame of the machine by brackets 68.

The operation of the machine is as follows: The wrappers are usually printed on sheets which contain a number of identical prints, as shown diagrammatically in Fig. 10. The sheets are six wrappers wide by seven wrappers long. The sheets are fed from the table 58 to the rollers 29 and 30 which feed the sheets into the machine, the folding rollers 47 and 49 acting also as feeding or delivering rollers to deliver the finished strips or wrappers into the tray 60.

15 As the sheet passes through the machine it is cut by the cutters 33 into strips along the lines "A—A" (Fig. 10). The cutting strips are then creased or crimped along the lines "B—B" by creasers 41 and 44; and the 20 creased strip then has its edge portions bent up or folded into a trough-like shape by the folding rollers 47 and 49. The thus partially folded strip delivered from the machine, is easy to completely fold, along the 25 creased lines, after the cigarette paper packets have been inserted,—this folding and filling being done either by hand or by separate machines. The completely folded and filled strips are then cut into separate packets by cutting along the lines C—C of Fig. 10.

I claim:

1. In a machine of the class described, the combination of means for successively cutting a sheet into strips, means for creasing the strips, means for folding the edge portions of the strips, means comprising a lower driven roller and an upper roller which is free to revolve for feeding the 35 sheets to the cutting means, each of said means including a lower revolute shaft, an upper revolute shaft and means for moving the upper shafts away from the lower shafts, means for folding the edge portions of the strips, said folding means comprising suitably shaped upper and lower members, a pivoted arm for supporting the upper member and means on said arm for applying a yielding pressure upon said upper member.

40 2. In a machine of the class described, the combination of means for successively cutting a sheet into strips, means for creasing the strips, means for folding the edge portions of the strips, means comprising a lower driven roller and an upper roller which is free to revolve for feeding the sheets to the cutting means, each of said means including a lower revolute shaft, an upper revolute shaft and means for moving the upper shafts away from the lower shafts.

45 2. In a machine of the class described, the combination of means for successively cutting a sheet into strips, means for creasing the strips, means for folding the edge portions of the strips, means for feeding the sheets to the cutting means, each of said means including a lower revolute shaft, an upper revolute shaft and means for moving the upper shafts away from the lower shafts, said means for moving the upper shaft of said feeding means being capable of operation independent of the other shaft moving means.

3. In a machine of the class described, the combination of means for successively cutting a sheet into strips, means for creasing the strips, means for folding the edge portions of the strips, means for feeding the sheets to the cutting means, each of said means including a lower revolute shaft, an upper revolute shaft and means for moving the upper shafts away from the lower shafts, said means for moving the upper shaft of said feeding means being capable of operation independent of the other shaft moving means.

3. In a machine of the class described, the combination of means for successively cutting a sheet into strips, means for creasing the strips, means for folding the edge portions of the strips, means for feeding the sheets to the cutting means, each of said means including a lower revolute shaft, an upper revolute shaft and means for moving the upper shafts away from the lower shafts, said means for moving the upper shaft of said folding means being capable of operation independent of the other shaft moving means.

4. In a machine of the class described, the combination of means for successively cutting a sheet into strips, means for creasing the strips, means for feeding the sheets to the cutting means, each of said means including a lower revolute shaft, an upper revolute shaft and means for moving the upper shafts away from the lower shafts, means for folding the edge portions of the strips, said folding means comprising suitably shaped upper and lower members, a pivoted arm for supporting the upper member and means on said arm for applying a yielding pressure upon said upper member.

5. Apparatus according to claim 4 including means for adjusting the arm relatively to the lower member.

In testimony whereof, I affix my signature.

ALEXANDER G. GORDON.
